UNITED STATES PATENT OFFICE.

BENJAMIN W. SEELEY, OF PENSACOLA, FLORIDA.

DETACHABLE EXTENSION CLAMP.

Application filed August 26, 1924. Serial No. 734,308.

To all whom it may concern:

Be it known that I, BENJAMIN W. SEELEY, a citizen of the United States, residing at Pensacola, in the county of Escambia and State of Florida, have invented certain new and useful Improvements in Detachable Extension Clamps; and I do hereby declare the following to be a full, clear, and exact description of the invention, such as will enable others skilled in the art to which it appertains to make and use the same.

This invention relates to carpenters' clamps, and has for its primary object the provision of a novel device of this character which shall be adapted to hold in assembled relation units of work varying in width from a fraction of an inch to several feet, which shall be simple and inexpensive to manufacture, and which may be readily taken apart so that the parts thereof may be compactly arranged for storage.

With the above and other objects in view, the invention consists in the construction, combination and arrangement of parts hereinafter fully described and claimed, and illustrated in the accompanying drawings, wherein:

Figure 1 is a view in side elevation of the clamp applied to a comparatively narrow unit of work,

Figure 2 is a bottom plan view of the clamp,

Figure 3 is a view in side elevation of the clamp applied to a comparatively wide unit of work,

Figure 4 is a detail sectional view taken on the plane indicated by the line 4-4 of Figure 1,

Figure 5 is a detail sectional view taken on the plane indicated by the line 5-5 of Figure 1,

Figure 6 is a detail sectional view taken on the plane indicated by the line 6-6 of Figure 1,

Figure 7 is a view in side elevation of the clamp applied to a unit of work with the bracket and pressure screw removed,

Figure 8 is a detail sectional view, illustrating a slightly modified form of the intermediate bar section, and

Figure 9 is a detail sectional view illustrating the formation of the openings in the jaws and bracket of the clamp.

Referring to the drawings by reference numerals, 1 designates the bar of my improved clamp. The bar is of sectional

formation, and it embodies terminal sections 2 and 3 and an intermediate section 4. The sections 2, 3 and 4 are adjustably connected together so as to permit the length of the bar 1 to be increased or decreased, they may be of any desired length, and they may be of the same or of different lengths. The terminal sections 2 and 3 are of hollow U-shaped

formation in cross section, and the intermediate section 4 is of solid U-shaped formation in cross section. The intermediate section 4 has a snug sliding fit within the terminal sections 2 and 3 to prevent the sections from having any relative lateral or twisting movements. These parts are pro-

vided with longitudinal rows of openings 2^a, 3^a and 4^a, respectively, to permit them to be secured in the required adjusted position by pins 5. Jaws 7 and 8 are slidably mounted upon the terminal sections 2 and 3, respectively, to permit them to be relatively adjusted.

The jaws 7 and 8 are provided with rows of openings 7^a and 8^a, respectively. These rows of openings are in alignment with the rows of openings 2^a and 3^a. The jaws 7 and 8 are secured in adjusted position by pins 9 passing through register-

ing openings in the jaws and terminal sections. The pins 5 pass through register- 85

ing openings in the terminal sections 2 and 3 and the intermediate section 4. The pins 9 are secured to their respective jaws by flexible elements 10 so as to prevent them from being misplaced or lost. A bracket 90

11 is slidably mounted upon the terminal section 3 outwardly beyond the jaw 8 for adjustment with respect to this jaw. The bracket 11 is provided with a row of openings 11^a arranged in alignment with the row 95

of openings 3^a, and it is secured in adjusted position by a pin 12 passing through a registering pair of these openings. This pin is secured to the bracket 11 by a flexible ele-

ment 13 so as to prevent its misplacement or loss. A pressure screw 14 has threaded connection with the bracket 11, and it is provided at its inner end with a swivelled head 15 for contact with the jaw 8, and at its outer end with a hand wheel 16.

As the sections 2, 3 and 4 of the bar 1 are connected together for relative endwise adjustment, as the jaws 7 and 8 are mounted upon the bar for relative adjustment, and as the bracket 11 is mounted upon the bar for adjustment with respect to the jaw 8, it should be apparent that the clamp may be

readily adapted for holding together units of work varying in width from a fraction of an inch to several feet.

In practice, after the bar 1 has been adjusted to the required length, the pressure screw 14 turned back, the jaw 8 freed and moved into contact with the head 15 of the pressure screw, and the jaw 7 adjusted on the bar 1 in the direction of the jaw 8 until the distance between these parts is slightly greater than the distance between opposite edges or sides of the unit of work, and the jaw 7 secured in adjusted position by its pin 9, the clamp is applied to the unit of work with the jaw 7 in contact with one edge or side thereof. The pressure screw 14 is then turned up until the parts of the work are under the desired pressure, after which the jaw 8 is secured against movement on the bar 1 by its pin 9. If desired, the bracket 11 and pressure screw 14 may now be removed and used in connection with another clamp comprising bar sections 2, 3 and 4, and the jaws 7 and 8.

In practice, the clamp may be provided with an additional section 4^c similar to the intermediate section 4 or 4^b if conditions require a bar longer than that provided for by the terminal section and a single intermediate section. The additional section 4^c is adjustably associated with one of the terminal sections, preferably the terminal section 2, as shown in Figure 7. A modified form of the intermediate section of the bar 1 is shown in Figure 8, and this section 4^b differs from the section 4 in that it is of hollow U-shaped formation. In practice, the clamp may be equipped with an intermediate bar section of solid U-shaped formation in cross section, as clearly shown in Figures 4, 5 and 6, or with the hollow U-shaped intermediate section shown in Figure 8.

In Figure 9 the formation of the bar receiving opening 7^a in the jaws 7 is illustrated. By reference to this figure, it will be seen that the end walls 7^b of the opening

are inclined in opposite directions in order to permit the jaw to be readily moved along the bar 1. The openings in the jaw 8 and bracket 11 are similar to the opening 7^a. 50

It should be understood that the drawings are merely illustrative and do not pretend to give exact proportions. Furthermore, the said drawings are illustrative of a preferred construction, it being my expectation that 55 various changes and modifications may be made without departing from the spirit and scope of my invention.

What is claimed is:—

1. A clamp comprising a bar embodying 60 terminal sections of hollow U-shaped formation in cross section and an intermediate section of solid U-shaped formation in cross section, the intermediate section being received by the terminal sections slidably to 65 permit the length of the bar to be varied, means adapted to secure the sections against movement with respect to each other, jaws carried by the bar, a bracket carried by the bar, and a pressure screw carried by the 70 bracket.

2. A clamp comprising a bar embodying 75 adjustably connected sections, certain of said sections being of hollow U-shaped formation in cross section and the other section being of solid U-shaped formation in cross section, means securing the sections in adjusted position, jaws mounted upon the bar, a bracket mounted upon the bar, and a pressure screw carried by the bracket. 80

3. A clamp comprising a bar embodying 85 adjustably associated terminal and intermediate sections of U-shape in cross section, the members of the terminal sections being hollow to receive the intermediate section, means for securing the sections in adjusted position, jaws mounted on the bar, a bracket mounted on the bar, and a pressure screw carried by the bracket.

In testimony whereof I affix my signature. 90

BENJAMIN W. SEELY.
